(57) **CLAIM**

The ornamental design for a sensor array, as shown and described.

DESCRIPTION

FIG. 1 is a front perspective view of the sensor array in accordance with an embodiment of the design;

FIG. 2 is a rear perspective view of the sensor array in accordance with an embodiment of the design;

FIG. 3 is a top view of the sensor array in accordance with an embodiment of the design;

FIG. 4 is a bottom view of the sensor array in accordance with an embodiment of the design; and

FIG. 5 is a view representing either side of the sensor array in accordance with an embodiment of the design; and,

FIG. 6 is a view representing either end of the sensor array in accordance with an embodiment of the design.

The features presented in dashed lines correspond to environment and do not form part of the claimed design.
